UNITED STATES PATENT OFFICE

158,413

SAMPLE PACKAGING BOX OR SIMILAR ARTICLE

Marvin Sherman, New York, N. Y., assignor to Young's Rubber Corporation, New York, N. Y., a corporation of New York

Application March 1, 1949, Serial No. 1,145

Term of patent 14 years

(Cl. D80—9)

To all whom it may concern:

Be it known that I, Marvin Sherman, a citizen of the United States, residing at 1085 Park Avenue, New York, New York, have invented a new, original, and ornamental Design for a Sample Packaging Box or Similar Article, of which the following is a specification, reference being had to the accompanying drawing, forming part thereof.

In the drawing:

Fig. 1 is a bottom view of a sample packaging box or similar article showing my new design.

Fig. 2 is a rear view; and

Fig. 3 is a top plan view thereof.

I claim:

The ornamental design for a sample packaging box or similar article, substantially as shown.

MARVIN SHERMAN.
